UNITED STATES PATENT OFFICE.

FREDERICK G. WACKER, OF CHICAGO, ILLINOIS.

CLOSURE FOR RECEPTACLE ORIFICES.

Application filed February 25, 1921. Serial No. 447,843.

To all whom it may concern:

Be it known that I, FREDERICK G. WACKER, a citizen of the United States, residing at Chicago, in the county of Cook 5 and State of Illinois, have invented certain new and useful Improvements in Closures for Receptacle Orifices, of which the following is a specification.

My invention relates to means for closing 10 receptacle orifices, and more particularly to bungs for metallic barrels, and consists in the combination of parts and features of construction hereinafter set forth and claimed.

15 In the drawing herein I have shown the embodiment of my invention. Fig. 1 is a plan view; Fig. 2 is a section on line 2—2 of Fig. 1; Fig. 3 is a section on line 3—3 of Fig. 1; Fig. 4 is a plan detail of the closure head proper; Fig. 5 is a detail thereof detached; and Fig. 6 is a detail of the bridge piece.

To the metal-sheet 10 of the barrel a ring 11 may be permanently connected in any 25 suitable fashion as by welding shown at 12, this rim having a circular chamber 13 terminating in the bottom seat 14 having an orifice 15. The head 16 to close said orifice has an annular flange 17 to overly the seat 30 and may carry a packing washer 18. This head has a recess 19 to receive the end portion 20 of the screw stem 21 having a suitable wrench-head 22 at its upper end. Permanently to secure the closure head 16 to the 35 stem to permit of its rotation thereon, the stem is formed with a reduced throat 23 into which a small flange portion 24 of the head 16 is spun.

On the stem 21, between the two heads, is 40 a threaded bridge piece 25 having opposed projecting lugs 26 that are adapted to contact with bayonet-lock passages formed in the interior wall of chamber 13. Diametrically opposed vertical passages 27 lead part-way down the wall of the chamber 13 and 45 with these passages communicate circum-

ferentially extending recesses 28, the front walls 29 of which constitute stops to prevent further forward rotation of the bridge piece and the top surfaces 30 of which afford 50 bearing for the tops of the lugs 26 as shown in Fig. 2.

To seal the orifice—one runs the threaded bridge piece to the bottom of the stem 21, drops the lugs in vertical channels 27 and 55 rotates the wrench-head in proper direction so that the lugs 26 are carried into the recesses 28 and there held against further rotation, so that the closure head 16 may be forced into sealing contact with the 60 seat 14.

I claim:

1. The combination of a ring structure having a chamber with a seat flange at its bottom, said chamber having bayonet-lock 65 passages above said flange, a bridge member having lugs to cooperate with said passages, an operating stem threaded through said bridge piece, and a closure head for cooperation with said seat flange, carried by the 70 lower end of said stem and rotatable with respect to but axially movable with said stem.

2. The combination with a sheet-metal wall, of a sealing-closure, construction therefore, comprising a ring structure secured to said wall and having an opening through said ring including a chamber affording a seat flange at the chamber-bottom, said chamber having bayonet-lock passages above 80 said flange; a bridge member having lugs to cooperate with said passages; an operating stem threaded through said bridge piece and having, at its lower end, a reduced 85 throat and a larger terminal portion, and a closure-head for cooperation with said seat flange, embracing said end-portion of the stem and engaging in the throat, whereby said head is carried by the lower end of said stem and rotatable with respect to but axially movable with, said stem. 90

FREDERICK G. WACKER.
